UNITED STATES PATENT OFFICE.

WILLIAM T. ASHCROFT, OF WATERBURY, CONNECTICUT.

WIRE-STRAIGHTENER.

1,012,964.

Specification of Letters Patent. Patented Dec. 26, 1911.

Application filed March 5, 1910. Serial No. 547,440.

To all whom it may concern:

Be it known that I, WILLIAM T. ASHCROFT, citizen of the United States, and resident of Waterbury, in the county of New Haven and State of Connecticut, have invented certain new and useful Improvements 5 in Wire-Straighteners, of which the following is a specification.

My invention relates to new and useful 10 improvements in wire straighteners, such as are used in connection with automatic wire working machines of various sorts, and through which the wire is fed from a reel.

It is the object of the invention to generally 15 improve upon devices of this kind and particularly to simplify and cheapen their construction so that the same can be made at a moderate cost; to provide a straightener that will operate upon different 20 sizes of wire and turn it out perfectly straight and suitable for any class of manufacture, causing very little scrap or waste when being used.

Further objects of the invention will hereinafter appear: and to these ends the invention consists of a device for carrying out the above objects, embodying the features of construction, combinations of elements, and arrangements of parts having 30 the general mode of operation, substantially as hereinafter fully described and claimed in this specification and shown in the accompanying drawings, in which—

Figure 1, is a top plan view of my improved 35 form of straightener. Fig. 2, shows a central vertical longitudinal section through the straightener with wire threaded therethrough. Fig. 3, is a vertical longitudinal section of the straightener mounted for rotation and with guide plug in lowered 40 position as when introducing the wire end, and Fig. 4, is a cross section of the straightener taken on line 4—4 of Fig. 2.

Referring to the drawings 5 represents a bracket for supporting the straightener and 45 6 a bearing of the bracket in which a pulley arbor 7 is supported and in which spindle of the straightener is rotatively mounted. The body 8 of this straightener is of a general 50 elongated cylindrical form though somewhat larger through its central portion 9 than the spindle ends 10. The wire 11 is passed longitudinally through the straightener, that is into one end and out from the other. The body 8 is slotted in one side as at 8' longitudinally from one

end to the other to form in part a passage way for the wire to be drawn through. This slot can be cut with a miller or other suitable machine by running the cutter 60 therof clear through the entire length of the body before the plug is put in position, which obviously means an inexpensive operation. The outer ends of this slot are reamed out slightly to form a socket for the 65 guide tubes 12 through which the wire is passed. A transverse bore 13 is formed through the enlarged central portion 9 of the body and in this bore is fitted a wire guide plug 14 having a cross groove 15 in 70 one end through which the wire is drawn in the manner shown in Fig. 2. A set screw 16 secured in the body serves to engage the plug and hold it in its adjusted positions 75 as for instance that shown in the drawings and whereby the wire is guided off from the center or direct line of travel through the straightener. This plug is thus made detached so that it can be lowered as shown 80 in Fig. 3, to permit the wire to be readily inserted, and after which the plug is again shoved out to the desired position and secured by the screw before mentioned. This serves as a great advantage in the introduction of thick wire which is hard to introduce through some forms of straighteners. The position of this plug may 85 obviously be varied according to the particular thickness and quality of wire to be straightened.

Should the tubes become worn and require to be changed they can be easily removed by loosening their set screws and other tubes substituted.

After the wire has been threaded through, 95 the plug is adjusted and secured in position, the straightener is suitably rotated during the feeding of the wire through the device. This form of treatment serves to bend the wire in various directions with the result 100 that it emerges from the tool perfectly straight.

It will be obvious that this straightener can be used in connection with different forms of wire working machines and also 105 in a different kind of arbors for driving the same, from that herein shown.

Having thus described my invention what I claim and desire to secure by Letters Patent is:—

In a rotary wire straightener of the class described, the combination of an elongated

tubular body having a longitudinal slot clear through one side thereof, guide tubes fitted in the two end portions of said slotted body, a plug adjustably fitted in a transverse bore, within the central portion of the body and intersecting the hole and slot of the body, a guide slot in the end of said plug, and a set screw for holding the plug in position.

Signed at Waterbury, in the county of 10
New Haven, and State of Connecticut, this
twenty-fifth day of February, A. D. 1910.

WILLIAM T. ASHCROFT.
